UNITED STATES PATENT OFFICE.

MARTIN L. WILLIAMS, OF MISHAWAKA, INDIANA.

GRINDING MACHINE.

Application filed February 18, 1922. Serial No. 537,388.

This invention relates to improvements in grinding machines and refers more particularly to a machine in which the cylinders of an engine may be ground automatically after 5 the amount of the cut has been ascertained and the cylinder block bolted in position.

Among the objects of the invention are to provide a grinding machine in which the grinding wheel while being driven at a high 10 rate of speed is slowly rotated about the inner walls of the cylinder due to the positioning of two eccentric sleeves in which the grinding spindle is mounted, and besides being accurately rotated about the cylinder 15 walls, the wheel is gradually and at a pre-determined rate of speed, fed to the bottom of the hole so that the grinding is effected in a uniform manner throughout the length of the cylinder, and the metal removed during 20 the grinding operation is uniform throughout the entire length of the hole.

Fig. 1 is a side view of the machine.

Fig. 2 is a front view of the machine.

Fig. 3 is a sectional view taken along the 25 line 3—3 in Fig. 4, looking in the direction of the arrows.

Fig. 4 is a view taken along the line 4—4 shown in Figs. 1 and 3 looking in the direction of the arrows.

Fig. 5 is a view taken along the line 5—5 30 in Fig. 4 looking in the direction of the arrows.

Fig. 6 is a view taken along the line 6—6 in Fig. 5.

Referring to the drawings there are three 35 major movements of the machine, the drives of which will be treated separately.

The first movement is the direct belt drive to the grinding wheel spindle. The second 40 is the drive to the eccentric sleeves by means of which the axis of the grinding wheel is rotated around within the cylinder which is being ground. The third drive is that which raises and lowers the head upon which the 45 grinding wheel is mounted. The lowering and raising of the head has to do with the feeding of the grinding wheel from the top of the hole to be ground to the bottom and raising it back to its original position where 50 it may be raised for a subsequent grinding operation. It is important in this regard to mention the fact that the entire mechanism is mounted upon the head which is raised and lowered by the feed last mentioned; that is, the grinding spindle, the eccentric 55 sleeves and the driving mechanism including

the motor, all are mounted upon the head which is raised and lowered on the frame during the grinding operation.

The major fixed portions of the machine 60 comprise a base 1 upon which is mounted an upright frame 2. This upright frame has an open portion 3 the sides of which are meshed in the form of ways 4. These ways have mounted thereon racks 5 which are engaged by gears in the raising and lowering of the head. The head unit which is raised and lowered on the frame may be considered as a unit 6 upon which is mounted the motor 7. To the head 6 are attached cables not 70 shown, which pass over pulleys positioned in the top pulley casings 8 and are fastened to counter balance weights 9 which are raised and lowered traveling opposite with the traveling of the head and serving to counter 75 balance the weight of the head. The frame is constructed to form wells 10 in which the counter balance weights are positioned.

The grinding wheel spindle drive consists in nothing more than a belt connection 11 80 between the pulley 12 mounted upon a motor 7 and pulley 13 mounted upon the grinding wheel spindle 14. An idler pulley 15 upon which is automatically imposed at all times a constant spring tension, contacts the belt 85 due to the spring pivot bearing 16.

The function of the automatic spring tensioned idler pulley is to maintain a constant tension upon the belt as there is a loosening and tightening effect produced by the eccentric sleeves in which the grinding wheel 90 is mounted.

The second drive is that to the outer eccentric sleeve which gives the rotative movement to the axis of the grinding wheel during the grinding operation. To the lower end of the motor shaft is fixed a pinion 17 which meshes with a gear 18 mounted upon the stud shaft 19 integral with the larger pinion 18 meshes with a gear 20 upon the vertical shaft 21. At the upper extremity of this vertical shaft is a bevel pinion 22 meshing with a second bevel 23 mounted on the shaft 24. Between the bearings supporting the shaft 24 are mounted two pinions 95 of different sizes, namely 25 and 26. These pinions mesh with larger pinions 27 and 28 respectively on a shaft 29 positioned below the shaft 24. These latter pinions 27 and 28 are loosely mounted upon the shaft 29 and are engageable with the clutch crab 30 which is manipulated through the connections 31 100 to 110

and 32 by means of a lever 33. These gears manipulated by the clutch give a variable speed change to the shaft 29 due to the differential gearing. At the forward extremity of the shaft 29 is mounted a bevel gear 34 meshing with the sleeve bevel 35 which is fixedly mounted upon the outer circumference of the sleeve 36. The sleeve 36 rotates upon an inner eccentric stationary sleeve 37. In the bottom of the inner sleeve is fitted an arbor 38 which carries the grinding wheel spindle 14. On the lower extension of the sleeve 37 is a gear 37^a which meshes with a worm 37^b. This worm in turn is meshed by a second worm wheel 37^c by means of which a micrometric setting of the sleeves relative each other may be made. This definite setting is made by means of a pointer fixed to the outer sleeve and registering with graduations made on the circumference of the lower sleeve at 37^d. The details as to the micrometric setting are unimportant to the invention other than the fact that the amount of eccentricity may be accurately set upon the sleeves prior to grinding. When the axes of the grinding wheel spindle and the two sleeves coincide, the grinding wheel is fed directly downward without rotative movement of its axis, but when the axes of the grinding wheel spindle and the sleeves do not coincide the axis of the grinding wheel spindle is given a rotative movement and it is fed downward during the grinding operation.

The vertical movement of the head produced by gears meshing with the racks 5 on the ways 4, gives the grinding wheel its vertical travel from the top to the bottom of the cylinder hole. This third drive is likewise taken from the motor through the same train of gears as that which drives the outer eccentric sleeve. The drive connections are identical to the driven shaft 29. On this shaft, in addition to the bevel gear 34, there is mounted centrally thereof a second bevel gear 39. Meshing with the bevel gear 39 is a second bevel gear 40 which is mounted in close relation to a second shaft 42. On shaft 41 are mounted different size gears 43 meshing with multiple gears 44 on the shaft 42. The small gears on the shaft 41 mesh with the larger gears on shaft 42 and vice versa. The shaft 41 is hollow to accommodate a slidable key arrangement 45 which is operated by handle 46. The gears 43 are rotatably mounted upon the shaft 41 while the multiple gears are fixedly mounted on the shaft 42, so by selecting any desired pinion or gear 43 by means of the slidable key 45 it is possible to select different speeds at which the shafts will be rotated. The drive from the shaft 41 to the shaft 42 is transmitted through a bevel gear 47 mounted on the outer extremity of the shaft. This gear meshes with two bevel gears 48 and 49 positioned

below and above the bevel gear and rotatably mounted on the vertical shaft 50. Between the bevel gears 48 and 49 is positioned a clutch crab 51 which is centrally grooved to accommodate the ring 52 of the clutch yoke 53. The upper and lower arms 53^a and 53^b of the clutch yoke bear on a secondary shaft 54 which is also vertically mounted in the reverse mechanism casing 55. Upper and lower latches 56 and 57 are notched at 58 to catch and hold projections 59 on the arms of the yoke when it is pushed up or down by means of the reverse handle 60 or the automatic tripping rod 61 and wedge 62 positioned on the extremity of the rod in connection with the upper yoke arm. Flat springs 63 overlie the latches so that they will at all times contact the arms of the yoke and drop into place behind the projections 59 when the yoke is moved to an up or down position.

The operation of the device is such that when it is desired to lower the head by means of the automatic feed, the handle 60 is pushed in so that the yoke which is pinned to the shaft 54, moves upward and the latch 57 drops behind the projection 59 and the clutch crab is caused to engage the upper bevel gear 49 so that the gear will rotate the shaft 50 to lower the head through the complete lowering drive hereafter more completely explained.

When the grinding wheel has moved to the bottom of the hole and it is desired to raise the head automatically, the handle 60 is pulled out, at which time the latch 57 is raised and the latch 56 dropping in place behind the projection 59 on the arm 53^a. By this movement of the yoke the clutch crab will engage the lower bevel gear 48 and cause the shaft 50 to rotate in the opposite direction to raise the head. Compression springs 64 are positioned about the shaft 54 between the arms 53^a and 53^b of the yoke to hold the yoke naturally in a neutral position as it appears in Fig. 5 when the automatic drive is not used.

There is positioned upon the outside frame shown in Fig. 1 an automatic tripping wedge 65 which is adjustable upon a way 66. This wedge is adjustable vertically along the way to limit the downward movement of the grinding wheel. It functions to trip the automatic push rod 61 when the head has moved downward to a position where the trip rod contacts with the wedge. The tripping of this push rod causes the wedge 62 to force the yoke 53 downwardly causing the clutch crab to engage the lower bevel gear and reverse the downward travel of the head so that it is automatically fed upward to its initial position. On the lower end of the shaft 50 is a bevel gear 67 meshing with the bevel gear 68 fixedly mounted upon the horizontal shaft 69 upon which are also

mounted pinions 70 and 71. These pinions mesh with larger pinions 72 and 73 rotatably mounted upon the shaft 74. Between the pinions is a clutch mechanism 75 which is operated through the arms 76 and 77 by the handle 78. In addition to the gears 72 and 73 there is mounted upon the shaft 74 a worm 79 meshing with a worm gear 80 on the shaft 81. This shaft extends horizontally across the entire frame and carries two pinions 82 which mesh with the racks 5 and serve to feed the head upward and downward in its reciprocating movement as the grinding wheel is fed from the top to the bottom of the cylinder cavity during the grinding operation. The purpose of the clutch mechanism 75 with the differential gearing which it controls is to supply a further speed change to the rate of travel in addition to the multiple speed supplied by the multiple gears 43 and 44 and the speed gear change controlled by the lever 33 and differential gearing on the shafts 24 and 29. If it is desired to raise or lower the head manually by means of the spider wheel 83 it is only necessary to slide the spoke wheel outwardly upon the shaft so that the crab 84 engages member 85 which is pinned to the shaft 81. At other times when the handle is pushed into a position shown in Fig. 4 and the crab 84 is out of engagement with the member 85, the spider wheel 83 turns freely upon the shaft 81. This is to prevent its rotation during the automatic feeding of the head. When manually operated the clutch mechanism 75 should be in neutral position as shown in Figs. 5 and 6 so that the shaft 74 will turn freely with the shaft 81. Thus it is possible to get a large number of speed gear changes in the speed of the vertical travel of the grinding wheel. The control is such that vertical speeds from seven thousand to one-quarter of an inch per revolution with a number of intermediate speeds may be produced. The mechanism is compact and all operating parts travel with the head during its vertical reciprocation.

I claim as my invention:

1. In a grinding machine, the combination with a frame having vertical supporting columns with a central longitudinal opening, of a head having mounted thereon an arbor enclosing a grinding wheel spindle, a mechanism for producing vertical reciprocation of the head, a motor mounted on the head for driving the respective mechanisms, the head and its elements reciprocating as a unit, eccentric means manually set and automatically operated for giving the axis of the grinding wheel spindle a rotative movement during the vertical reciprocation of the head.

2. In a grinding machine, the combination with a frame having spaced vertical supporting columns, of a reciprocating head having mounted thereon a grinding

wheel spindle, a mechanism communicating through the spaced columns for producing vertical reciprocation of the head, a motor for driving the respective mechanisms, said elements mounted on and reciprocating with the head, eccentric means manually set and automatically operated for moving the axis of the grinding wheel spindle in a circular orbit during the vertical reciprocation of the head.

3. In a grinding machine, the combination with a frame having spaced vertical supporting columns, of a balanced head having mounted on one end and reciprocating therewith as a unit, a grinding wheel spindle, a mechanism for producing vertical reciprocation of the head and a motor mounted on the opposite end of the head and moving with it for driving the respective mechanisms, eccentric means adapted to be manually set to a micrometric scale and automatically driven for moving the axis of the grinding wheel spindle in a circular orbit during the vertical reciprocation of the head.

4. In a grinding machine, the combination with a frame, of a balanced head having mounted on one end thereof and integrally functioning therewith, a grinding spindle, a mechanism for producing vertical reciprocation of the head, and a motor mounted on the opposite end and integrally functioning therewith for driving the respective mechanisms, said reciprocating mechanism driven through a series of differential gear trains from the motor.

5. In a grinding machine, the combination with a frame of a head vertically movable upon the frame and having mounted thereon and reciprocating therewith, a grinding wheel spindle, a mechanism for producing longitudinal reciprocation of the head, and a motor mounted on the head and movable therewith for driving the respective mechanisms, means mounted on the frame cooperating with means on the head for reversing the travel of the head at a predetermined point.

6. In a grinding machine, the combination with a frame having spaced vertical supporting columns, of a balanced head having mounted thereon an arbor enclosing a grinding wheel spindle, a mechanism for producing vertical reciprocation of the head, a motor mounted on and reciprocating with the head for rotating the grinding wheel spindle, the head and its elements reciprocating as a unit.

7. In a grinding machine, the combination with a frame having spaced vertical supporting columns, of a balanced reciprocating head having mounted thereon a grinding wheel spindle, a mechanism communicating through the spaced columns for producing vertical reciprocation of the head, a motor for rotating the grinding wheel spindle, said

motor mounted on and reciprocating with the head.

8. In a vertical grinding machine, the combination with a frame having spaced vertical supporting columns, of a balanced head vertically movable in the space between the vertical columns and having mounted thereon and reciprocating therewith a grinding wheel spindle, and a motor mounted on

the head and movable therewith for rotating 10 the grinding wheel spindle, a mechanism for producing longitudinal reciprocation of the head and means mounted on the frame operated by contacting means on the head for reversing the travel of the head at a pre- 15 determined point.

MARTIN L. WILLIAMS.
